a six plate wood stove, and I do hereby certify that the annexed drawings are full and accurate delineations of the arranged parts, with their several ornaments, to the side plate, which is not represented being similar to the one represented and where portions of plates are shewn, the portions not shewn being symmetrical with them, and similarly ornamented.

(What I claim as my production)
and desire to secure by Letters Patent, is the combination and arrangement of ornamental figures and forms represented in and by the accompanying drawings forming together an ornamental design for a six plate stove.
